(57) **CLAIM**

The ornamental design for a toothbrush, as shown and described.

DESCRIPTION

FIG. 1 is a perspective view from the right side of a toothbrush showing our design;

FIG. 2 is a top plan view thereof;

FIG. 3 is a bottom plan view thereof;

FIG. 4 is a left side elevational view thereof, it being understood that the right side view is a mirror image;

FIG. 5 is a view from the head end thereof;

FIG. 6 is a view from the handle end thereof;

FIG. 7 is a perspective view from the right side of a second embodiment of the design shown in FIGS. 1-6;

FIG. 8 is a top plan view of FIG. 7;

FIG. 9 is a bottom plan view of FIG. 7;

FIG. 10 is a left side elevational view of FIG. 7, it being understood that the right side view is a mirror image;

FIG. 11 is a view from the head end of FIG. 7;

FIG. 12 is a view from the handle end of FIG. 7;

FIG. 13 is a perspective view from the right side of a third embodiment showing a handle of our toothbrush, with the broken line showing bristles being of illustrative purposes only and forming no part of this embodiment;

FIG. 14 is a top plan view of FIG. 13;

FIG. 15 is a bottom plan view of FIG. 13;

FIG. 16 is a left side elevational view of FIG. 13, it being understood that the right side view is a mirror image;

FIG. 17 is a view from the head end of FIG. 13; and,

FIG. 18 is a view from the handle end of FIG. 13.
